UNITED STATES PATENT OFFICE.

VANDIVER J. VAN HORN, OF CHICAGO, ILLINOIS.

SEWING-MACHINE.

1,264,714.

Specification of Letters Patent. Patented Apr. 30, 1918.

Application filed October 12, 1915. Serial No. 55,382.

To all whom it may concern:

Be it known that I, VANDIVER J. VAN HORN, a citizen of the United States, residing at Chicago, in the county of Cook and 5 State of Illinois, have invented certain new and useful Improvements in Sewing-Machines, of which the following is a specification.

My invention relates to improvements in 10 stitch-forming mechanism for sewing machines. One of its objects is to provide a mechanism for making a plural-thread stitch wherein the thread-handling members that 15 coöperate with the needle, for the formation of the desired thread-concatenation, are non-thread carrying, and are uni-directionally rotatable.

In my prior Patent No. 1,136,299 dated April 20th, 1915, some of the claimed features whereof are embodied in the present machine, I have shown and described mechanism for the formation of a single-thread chain stitch, such mechanism providing for coöperation with the usual needle, a loop 25 handler that is formed as an arcuate band and that is revoluble to pass endwise completely through the loop which it holds, in the exercise of its intended functions. Furthermore, in my prior Patent No. 1,143,795 30 dated June 22, 1915, I have shown and described mechanism for the formation of a plural-thread chain stitch, some of the claimed features whereof are embodied in my present machine, such mechanism employing a single uni-directionally-rotatable, 35 arcuate-band-form, loop handler but in co-operation with a second thread handler that carries the second thread and works transversely to the rotational plane of the first 40 said member. By each such construction I have provided for the attainment of objects valuable in sewing machinery, such as elimination of take up mechanism, minimization of the quantity of thread drawn off and 45 handled in connection with the formation of each stitch, firm and advantageous setting of each stitch, the simplification of, and condensation of size of, working parts; the provision of structure susceptible of very 50 high speed operation, and the like; and it will be understood that it is further in pursuance of, and for most satisfactory attainment of, these and other objects that my present invention is designed.

55 Specifically an object of my present invention is to provide a construction for the

formation of a plural thread stitch, such as a double-thread chain stitch, doing away with non-rotating thread-handling parts, and providing for each thread employed in 60 the stitch formation, a rotatable band-like thread retainer arranged to perform its functions during its endwise passage past the area of stitch-formation or, in other words, past the "stitchmaking point." 65

A further specific object is to provide simple and adequate driving means whereby the desired rotation may be imparted to such members.

Another object is to construct the said 70 mechanism in such compact and simple form that, if desired, a plurality of said mechanisms for coöperation with a plurality of needles may readily be placed side by side to be mutually driven from a common shaft. 75

In the drawings I have shown my invention embodied only in a machine for making a "double thread chain" stitch, but it will be understood that features of my invention herein claimed are not restricted to such embodiment but are adaptable, within the generic idea of my invention, to specific embodiments for operation in forming other kinds of stitches in which loops of a thread or threads will be interengaged. For purposes of full disclosure, however, of one particular embodiment of my invention I will confine the specific description thereof to the single exemplification shown, but without intent thereby to limit my invention in 90 this regard further than as set forth in the claims. 85

In the drawings

Figure 1 is an end elevation, conventionalized, of a sewing machine stitch forming 95 mechanism embodying my invention;

Fig. 2 is a vertical section through a portion thereof on line 2—2 of Fig. 4;

Fig. 3 is a vertical section, looking in the opposite direction, on line 3—3 of Fig. 4; 100

Fig. 4 is a transverse section on line 4—4 of Fig. 3;

Fig. 5 is a broken elevation showing the parts illustrated in Fig. 3 in a different relation. 105

Fig. 6 is a vertical section on line 6—6 of Fig. 5; and

Fig. 7 is an extended perspective showing the parts ready for assemblage and mounting on the shaft. 110

Figs. 8, 9, 10 and 11 are diagrammatic views illustrating, in planar form, purely

for explanatory purposes, the thread handling parts in several positions of progress past the stitch making point.

Fig. 12 illustrates the thread concatenation, showing a few "set" stitches and others with the threads diagrammatically spread for clear display.

Referring to the drawings the sewing machine may comprise any suitable head A, 10 presser foot B, slotted work-plate C, and suitable feed mechanism (not shown). With the nature of these (or equivalent) mechanisms for presenting and feeding work relative to the eye pointed needle *n*, my 15 present invention has no direct concern, but it will be understood that by the employment of features of my present invention the use of a "take-up" for the needle thread *t* (and also for the second thread *t'* hereafter 20 referred to) is made unnecessary, so that the needle thread may pass direct to the needle from the tension device D and the second thread may be acted on by any suitable tension device diagrammatically shown 25 at D'. In the general arrangement of the parts so far referred to there is nothing peculiar or novel. The fabric or fabrics *f* (see Fig. 8) to be stitched are fed between the presser foot B and the work plate C, and 30 the needle in its descent may penetrate therethrough and, by partial retraction, throw out a loop 1, of needle thread *t*, below the work as shown in Fig. 8, to be engaged with other thread-loops in the desired concatenation.

In the formation of the double thread chain stitch, for which the mechanism herein specifically shown is particularly designed, a second thread *t'* is employed, and 40 the general mode of operation, for proper interlooping of the threads, is as follows: Each time the needle effects a penetration and retracts sufficiently to throw out a loop 1 of the thread *t*, such loop 1 is held below 45 the cloth while the needle fully retracts and a work-feed takes place; the loop 2 of the second thread is passed through the loop 1 of needle thread, as illustrated in Fig. 10, just before the needle descends again, and 50 on its said next descent the needle *n* passes through this second-thread loop 2, and throws out its next succeeding needle thread loop 1^a, whereupon the cycle is repeated, such 55 repeated cycles resulting in a thread concatenation that is clearly illustrated in Fig. 12. Of course, the stitch *per se* is old and well known.

Preliminarily, to an explanation of the detailed mechanical structure in which my 60 invention finds its present embodiment, the principle of operation of my structure may readily be understood with reference to the diagrammatic views, Figs. 8 to 11, wherein the thread-handling parts that coöperate 65 with the needle are shown as straight, in-

stead of arcuate, and wherein only the parts acting on the thread are shown, without reference to any means of support or driving means, for diagrammatic simplicity.

When the needle *n* has descended through 70 the fabric *f*, and has partly retracted to throw out its loop 1, a thread-handling band 20, having a point 21 at its forward end, passes alongside the needle through the needle thread loop 1, so that, as shown in 75 Fig. 9, when the needle retracts the loop 1 is held in properly open condition by the band 20. The loop is not materially enlarged, but is merely retained in what we may term a static condition, so to speak, while the band 80 20 travels forward therethrough. Over this first said band 20 there is arranged a second thread-handling band 25 that travels in the same direction with, and at the same speed as, the band 20. This second band is pref- 85 erably slightly narrower than the band 20 so as to pass easily through the loop 1, its point 26 is back of the point 21 in direction of travel; and the second band spaced apart from the band 20 sufficiently far to permit 90 the second thread *t'* to pass easily between the two bands. This second thread *t'* may be presented at a proper elevation, just above the band 20 and below the band 25 by guid- 95 ance through an eyelet 32 so that inevitably the point 26 of the second band 25 may pass over the affected portion of the thread *t'*. In consequence, during the major portion of the time that the two bands 20 and 25 are 100 passing endwise through the loop 1, the sec- 105 ond thread *t'* lies idly in the interspace be- 110 tween the two bands. And it is while the threads are thus in static condition, merely positioned for the action that is subsequently to interloop them, that the feed takes place moving the fabrics in a direction opposite to the direction of passage of the bands 20, 25, and so shifting the needle thread loop, 1, a bit rearwardly along the bands, as suggest- 115 ed in Fig. 10.

On one of the bands—preferably the first mentioned band 20—there is a projection 22 for coöperation with the second thread *t'*. It comes into action after the aforesaid feed has taken place. As herein shown this mem- 120 ber takes the form of a U-shaped rib open between the limbs of the U, and projecting upwardly from the rear end of band 20, in rear, (generally speaking) of the end of the upper band 25, the separation between pro- 125 jection 22 and band 25 being sufficient for thread-clearance. This U-shaped rib project- 130 ing upwardly from band 20 (across which lies thread *t'*), on its forward move- ment forms and carries forward through loop 1 of thread *t* a secondary loop 2 formed in thread *t'*. The timing of the parts is such that as the needle makes its second de- 135 scent through the fabric (Fig. 10) it will pass down within the confines of the U-

shaped rib 22 aforesaid, of the band 20. The result of this coördination is graphically shown in Fig. 10: The feed of the goods in a direction opposed to the travel 5 of the bands 20—25 has drawn the whole loop 1, that is being retained by the band 20, somewhat back of the vertical line of needle descent; the second thread t' has been engaged by the U-shaped rib 22 of the member 10 20 and has been carried forward somewhat thereby in the form of a secondary loop 2 which is thereby passed through the primary loop 1; and next the needle, descending into the interior of the U-shaped rib 22, will pass 15 its next primary loop 1^a down through the secondary loop 2 of the second thread. Proper tension devices acting on the threads t and t' resist their being drawn out into loop form and the resistance thus imposed on 20 thread t' will be sufficient to insure that said secondary loop 2 will slip off of the properly beveled and rounded surfaces of the rib 22 after the needle has passed down into the said secondary loop 2. Consequently the 25 "shedding" of the loop 2 from the rib 22 leaves it lassoed around the needle n (as shown in Fig. 11) when, in the continuing progress of the machine cycle, the band 20 engages afresh with the needle thread, taking 30 this newly formed loop 1^a, and starting a new cycle of operations under the same conditions that are shown in Fig. 8. Constant repetition of this cycle of operation obviously results in the enchaining of the two 35 threads in the fashion shown in Fig. 12.

Aside from the structural details (hereafter to be explained) for one effective embodiment of my invention, it will be apparent to those skilled in the art that the 40 structural principles exemplified in the diagrammatic views are highly advantageous. The interengagement of the thread loops on the under side, or "wrong" side, of the fabric is accomplished wholly by endwise moving 45 bands, traveling always in the same direction; and these bands may be driven in constant time-relation to the main shaft. Such unidirectional, uniform-time movement is very advantageous in a high speed 50 mechanism. The linear extent of such bands may be selected primarily on the basis of mechanical expediency in construction and in practice may be widely varied, for the reason that increase or decrease in 55 length of the band 20, (with corresponding proportioning of the correlated band 25) will manifestly have no effect upon the amount of thread drawn off by such bands in their functional operations. This disassociation of the linear dimension of the 60 thread-handling parts from any controlling relation to the amount of thread handled is mechanically of great importance and gives the mechanism susceptibility to many adaptive variations in design to meet particular

machine requirements. Furthermore, as to each thread employed in producing the desired concatenation of threads, no more thread is drawn into looped form at any time than is necessary merely to secure the 70 desired interloopage, and the loop forming elements themselves (*i. e.* the needle which forms the needle thread-loop and the U-shaped rim operating with the second thread to make the loop-bend therein,) will act, 75 in forming each respective thread loop, to set the thread of the preceding stitch, thereby obviating the necessity for any independent take-up devices, so doing away with a train of auxiliary mechanism. Also 80 the relation of the bands enables the two threads to be positioned with respect thereto in such positive fashion that skipping of stitches is substantially impossible. And further, the only thread that need be passed 85 through an eye in a moving part is the needle thread. Many other advantages due to the underlying principle of mechanical construction will be apparent to those skilled in the art, but the foregoing brief suggestion of a few characteristics of the present invention will suffice to indicate its novelty 90 and utility, and to indicate that the invention does not reside primarily in details of the single embodiment that is specifically 95 shown.

Referring now to the particular mechanical embodiment of my invention shown in detail herein, I provide below the work plate C an annular race-way 15, flattened at its 100 top and otherwise circular, said raceway having an opening 16 immediately through its flattened part below the work plate. The annulus has a recess 17 and in its end wall has concentric grooves 18 and 19 in which the rotatable bands 20 and 25 respectively are mounted. The inner, lower, or primary band 20 has its point 21 adjacent its transverse center so that its pointed end may travel very close to the needle for the purpose of taking the needle thread loop, and at its rear end it has the outwardly projecting U-shaped rib 22, having its external surfaces somewhat tapered toward the crest of the rib for proper thread-shedding purposes, and having between the limbs of the ribs the needle receiving opening 23. Diametrically opposed slots or openings 24 are made in the band to coöperate with the driving shoes to be described. 110

The outer, upper, or secondary band 25, shorter than the band 20, has its point 26 preferably adjacent that side thereof which is guided in the circular guide way 19. Preferably the second band 25 is somewhat 125 narrower than the band 20 (see Fig. 4) so that it may easily travel through the primary or needle-thread loop that is retained by the band 20. This secondary band 25 is provided with slots 24' radially registering 130

with the slots 24 on the inner band 20, and at its rear end, (that, in a general way, terminates just in front of the rim 22,) it preferably has a finger 27 that extends along 5 beside the loop-forming projection or rim 22 to afford some slight retardation to complete thread-shedding from said rim, sufficiently retarding the loop-shedding to insure that the secondary loop will be caught by the descending needle.

Since the inner or lower band 20 must always pass below the second thread, and the outer or upper band 25 above such thread, I preferably provide a guide for the 15 second thread so arranged as positively to lead the second thread into the interspace between the two said bands. To this end, I mount a thread guide 30 to span the opening 16 in the race-way ring 15 and on said 20 thread guide I form a nose 31 that projects into the interspace between the two grooves 18 and 19 in which the two bands are guided. The thread opening 32 in such guide may communicate, with angularly disposed 25 slots 33 and 34 indirectly leading to the upper edge of the guide bridge so that the threading of the thread-guide may be very readily and positively accomplished by passing the second thread laterally into the 30 slots.

The two bands 20, 25 may be driven in rotation in constant time relation to the main shaft of the machine by any suitable mechanism that will exert its driving influence on the band always at such point or points as to leave the portion of the bands passing the stitch making point wholly free, thus, of course, to prevent the driving devices from interfering with the proper handling 35 of the threads which lie always at or adjacent to such stitch making point. In the particular construction shown, and constituting one effective and desirable driving means, I mount on the drive shaft 40 a driving head 41 that fits neatly within the annular race-way 15, preferably securing such head to the shaft by a split clamp 42 fastened by a tension screw 43 to the shaft and by a connection screw 44 to the opening 45 40 in the head. Across that face of the head 41 which I may term its inner face, (*i. e.*, the face away from the observer in Fig. 1) I form a diametrical slot 47 in which are mounted sliding shoes 48, each having a point 49 that may pass through the registering openings 24 and 24' in the two bands, and each having an anti-friction roller 50 projecting beyond the head 41. The recessed raceway 15 is overlain on its inner side by a 45 cover plate 51 having therein a cam groove 52 suitable to receive the anti-friction rollers 50 of the driving shoes, and such cam groove being shaped so that as either shoe, during the rotation of the head 41, approaches the stitch making point, the por-

tion 52' of the cam groove will retract said shoe out of driving engagement with both of the bands 20-25, so leaving them wholly free as they pass the stitch making point where they perform their thread handling 70 functions. Thus in Fig. 4, one shoe is shown in full driving engagement with both of the bands, and the other shoe as passing out of engagement with both of the bands, having not yet completed its disengagement from 75 band 20.

Of course the driving head 41 must not interfere with the proper penetration of the needle, and therefore, as best illustrated in Figs. 5 and 6, it is provided with a suitable 80 recess 60 in its periphery to receive the needle, one edge of the needle-receiving portion being left in full circular form as illustrated in Fig. 1 and the other being cut away, as at 62, thus to insure the needle 85 thread loop being thrown out on the proper side of the needle, as will be well understood by those skilled in the art. Also, as a refinement, I preferably provide in the periphery of the driving head a diagonal slot 90 64 constituting in effect a thread guard, by which any loose thread, lint, or the like, that may accidentally get inside the inner band 20 and that would tend to clog the operation of the machine, may effectively be severed by the diagonal edge of the slot and gathered into the slot.

It will be apparent to those skilled in the art in the formation of a stitch involving secondary loops interengaged with primary loops—a condition present in a double thread chain stitch for specific example—I employ in the thread handling devices that coöperate with the needle, only unidirectionally rotatable parts, working in constant time with the driving shaft and so acting that no loop is formed of any substantially greater extent than is requisite to secure the intended interloopage of thread, and so that all 100 stitches are set by the loop-forming mechanisms themselves. As far as I am aware, I am the first to provide mechanism so characterized.

Further, it will be obvious to those skilled in the art that the entire structure below the race-way is very narrow, and may by mere design be made even narrower than that herein shown, so that if it be desired to mount a plurality of these structures on a single shaft in association with a like plurality of needles, the structural principle of my invention lends itself adequately to such multiplication of parts.

It will be understood by those skilled in the art that many changes in specific construction and design, in carrying forth the application of my present invention, may be made without departure from the spirit and scope of the invention, and that in their broader aspects the claims appended are not 125 130

intended to be restricted to the specific details of construction further than as therein specified.

Having described my invention, what I claim is:—

- 5 1. In a sewing machine, means for inter-engaging secondary loops with primary loops comprising, in combination with a tension device, a unidirectionally rotating member adapted to form a secondary loop, pass it through a primary loop, and, simultaneously with such secondary loop formation, set the secondary loop of the preceding stitch.
- 10 2. In a sewing machine, means for inter-engaging secondary loops with primary loops comprising, in combination with a tensioning device, a unidirectionally rotating member adapted to form a secondary loop and pass it through a primary loop, and also, simultaneously with such secondary loop formation, set the secondary loop of the preceding stitch and draw through the tensioning device only such thread as is necessary to the formation of the new secondary loop.
- 15 3. In a sewing machine, means for inter-engaging secondary loops with primary loops comprising a unidirectionally rotatable member adapted to maintain a primary loop in distended position for a definite period and to form a secondary loop, pass the latter through the former, and simultaneously set a previously formed secondary loop.
- 20 4. Means for forming a plural thread chain stitch comprising, in combination with a reciprocating needle for laying primary loops at a stitch-forming point, a plurality of unidirectionally rotatable members for respectively positioning the plural threads, said members providing means for inter-looping said threads and shedding the same in the course of their endwise rotary movement past the stitch forming point.
- 25 5. In a sewing machine, means for inter-engaging secondary loops with primary loops comprising a plurality of unidirectionally rotating members arranged jointly to pass endwise through a primary loop, positioning the primary loop in distended position and appropriately retaining the thread to form a secondary loop, one of said members having means for engaging the last said thread to form it into a secondary loop and pass it through the primary loop.
- 30 6. In a sewing machine, means for inter-engaging secondary loops with primary loops comprising a unidirectionally rotating primary member adapted to maintain a primary loop in distended position for a definite period, a secondary member rotating in unison with said primary member for holding, in appropriate relation to said primary

loop, and means associated with said members for forming the secondary loop and passing it through the primary loop.

7. In a sewing machine, means for inter-engaging secondary loops with primary loops comprising a unidirectionally rotating primary member adapted to maintain a primary loop in distended position for a definite period, a secondary member rotating in unison with said primary member for holding, in appropriate relation to said primary member, thread for forming a secondary loop, and means carried by the primary member for forming the secondary loop and passing it through the primary loop.

8. In a sewing machine, means for inter-engaging secondary loops with primary loops comprising a unidirectionally rotating primary member adapted to pass endwise through a primary loop and retain it in substantially uniformly-distended position for a definite period, a secondary member rotating in unison with said primary member passing through said primary loop and holding, in appropriate relation to said primary member, thread for forming a secondary loop, and means on one of said members for forming the secondary loop and passing it through the primary loop.

9. In a sewing machine, means for inter-engaging secondary loops with primary loops comprising a unidirectionally rotating primary member adapted to pass endwise through a primary loop and retain it in substantially uniformly distended position for a definite period, a secondary member rotating in unison with said primary member passing through said primary loop and holding, in appropriate relation to said primary member, thread for forming a secondary loop, and means on one of said members for forming the secondary loop and passing it through the primary loop, the last mentioned means drawing off only such thread as is necessary to form the secondary loop.

10. In a sewing machine, a driving shaft, a reciprocating needle operable in predetermined time-relation to said shaft, means for interengaging primary and secondary loops, comprising a rotating member unidirectionally driven in constant time with the driving shaft and adapted to form a secondary loop and pass it through the primary loop for engagement by the next formed primary loop, said member arranged to tighten the previously formed secondary loop by its formation of the new secondary loop.

11. In a sewing machine, a shaft, a reciprocating needle operable in predetermined time-relation to said shaft, means for interengaging primary and secondary loops, comprising a rotating member unidirectionally driven in constant time with the driving shaft, said member arranged for passage endwise through the primary loop and

adapted to form a secondary loop and pass it through the primary loop for engagement by the next formed primary loop, said member arranged to tighten the previously formed secondary loop by its formation of the new secondary loop.

12. In a sewing machine, a driving shaft, a reciprocating needle operable in predetermined time-relation to said shaft, means for interengaging primary and secondary loops, comprising a tensioning device, a rotating member unidirectionally driven in constant time with the driving shaft, said member arranged for passage endwise through the primary loop and adapted to form a secondary loop and pass it through the primary loop for engagement by the next formed primary loop, said member arranged to tighten the previously formed secondary loop by its formation of the new secondary loop and drawing through the tensioning device only such thread as is necessary to the formation of the new secondary loop.

13. In a sewing machine for forming a plural thread chain stitch, the combination with a drive shaft, of a reciprocating needle operable in predetermined time-relation to said shaft, a primary needle-carried thread, a tensioning device for said thread, a secondary thread, and means for interengaging primary and secondary loops formed in said threads respectively, comprising a rotating member unidirectionally driven in constant time with the driving shaft, said member arranged for passage endwise through the primary loop and adapted to form a secondary loop and pass it through the primary loop for engagement by the next formed primary loop, said member arranged to tighten the previously formed secondary loop by its formation of the new secondary loop.

14. In a sewing machine, means for interengaging secondary loops with primary loops, comprising a plurality of rotatable arcuate bands, means for rotating them in harmony to pass them endwise through a primary loop to maintain the primary loop in distended condition and maintain thread for the formation of a secondary loop in appropriate relation to the primary distended loop, one of said bands bearing means for forming the secondary loop, passing it through the primary loop and positioning it to receive the next-formed primary loop.

15. In a sewing machine, means for interengaging secondary loops with primary loops, comprising primary and secondary rotatable parti-circular bands, means for rotating them in harmony to pass them endwise through a primary loop to maintain the primary loop in distended condition and maintain thread for the formation of a secondary loop in appropriate relation to the primary distended loop, one of said

bands bearing means for forming the secondary loop, passing it through the primary loop and positioning it to receive the next-formed primary loop and the other serving to position the thread for secondary loop formation.

16. In a sewing machine the combination with a reciprocating needle for forming a series of primary loops of thread in spaced relation, means for engaging secondary loops formed from a different thread with said primary loops comprising a plurality of unidirectionally rotatable bands arranged to pass endwise through each primary loop to maintain it distended during their passage, and also retaining in appropriate relation to the primary loop thread for the formation of a secondary loop, and means carried by one of said bands for forming the secondary loop and passing it through the primary loop into position to receive the next-formed primary loop.

17. In a sewing machine the combination with the reciprocating needle for forming a series of spaced primary loops, of a primary arcuate band, an overlying concentric secondary arcuate band, means for driving said bands in unidirectional rotation and passing them endwise through each primary loop, to hold the primary loop distended during their passage and to present thread for the formation of a secondary loop in appropriate relation to the primary loop, one of said bands having means for temporarily engaging the last said thread in passage, to form it into a secondary loop and pass such secondary loop through the primary loop into position to receive the next formed primary loop.

18. In a sewing machine, the combination with a reciprocating needle for forming a series of spaced primary loops, and tension means to resist the loop-forming pull of the needle; of means for interengaging secondary loops with the primary loops comprising a plurality of unidirectionally rotatable members, means for rotating them to pass them through each primary loop, to maintain said primary loop distended during their passage and to position thread for the formation of a secondary loop in appropriate relation to the primary loop, one of said members carrying means for forming a secondary loop and passing it through the primary loop into position to receive the next formed primary loop; and tension means to resist the loop-forming pull of said means for forming the secondary loop.

19. In a sewing machine, means for forming a double thread chain stitch comprising, in combination with the feed and a reciprocating needle, concentric unidirectionally rotatable bands, means for driving them in unidirectional rotation endwise through each primary needle-thread loop,

whereby the lower band may hold the needle thread loop in substantially-uniform distended condition during its passage, and the other band may hold a second thread 5 transversely across the primary loop during a portion of its passage, one of said bands provided with a loop-forming projection for drawing said second thread in loop form through the primary loop and presenting it in position to receive the next primary 10 loop, before the first mentioned primary loop is shed.

20. In a stitch forming mechanism a circular raceway having an opening defining 15 a stitch forming point, a plurality of arcuate endwise traveling bands guidedly supported in said raceway in spaced relation, means for driving said bands unidirectionally in rotation, said means disengaging said 20 bands during passage of said means past said opening, one of said bands having on the rearward portion thereof a thread engag- 25 gaging projection.

21. In a sewing machine stitch forming 25 mechanism, a rotatable arcuate band, means for driving the same in rotation comprising a rotatable head, a pair of independently 30 radially movable band-engaging means carried by said head, and cam means controlling the movements of each of said band engag- 35 gaging means.

22. In a sewing machine stitch forming mechanism, a plurality of radially spaced

concentric bands, a thread carrying needle 35 coöperating with one of said bands, a second-thread guide opening to the inter-space between said bands, and means associated with said bands for interlooping the second thread with the needle-carried thread.

23. In a sewing machine stitch forming 40 mechanism, a plurality of radially spaced concentric bands, a thread carrying needle coöperating with one of said bands, a second-thread guide extending parallel to the axis of the concentric bands and opening to 45 the interspace between said bands, and means associated with said bands for interlooping the second thread with the needle-carried thread.

24. In a sewing machine stitch-forming 50 mechanism, a raceway having concentric grooves and an opening transverse to said grooves, two arcuate bands of different angular extent rotatable in said grooves, a rotatable driver-head partially encompassed 55 by said bands, and means carried by said driver head arranged to engage both said bands as points at all times remote from the raceway opening.

In testimony whereof I hereunto set my 60 hand in the presence of two subscribing witnesses.

VANDIVER J. VAN HORN.

In the presence of—

FORÉE BAIN,
MARY F. ALLEN.
